Primary Examiner—Nelson C. Holtje

(57) **CLAIM**

The ornamental design for a wrist-watch, as shown and described.

DESCRIPTION

FIG. 1 is a front elevational view of a wrist-watch showing my new design;

FIG. 2 is a rear elevational view thereof;

FIG. 3 is a right side elevational view thereof; and,

FIG. 4 is a perspective view thereof.

The dial and band are shown in broken lines for illustrative purposes only and forms no part of the claimed design.
